TOTE CASE FOR TABLEWARE OR THE LIKE

Martin A. Jaffe, Bronx, George S. Northrop, Wantagh,
and Samuel Braun, Rye, N.Y., assignors to Cellu-Craft
Inc., Lake Success, N.Y.

Filed Aug. 12, 1970, Ser. No. 44,424

Term of patent 14 years

Int. Cl. D3—99

U.S. Cl. D87—1

FIG. 2

FIG. 3

FIG. 4

FIG. 5

FIG. 6

FIG. 1

FIG. 1 is a front perspective view of a tote case for tableware or the like showing our new design with the cover open;

FIG. 2 is a front elevational view;

FIG. 3 is a rear elevational view;

FIG. 4 is a side elevational view, the opposite side being the same as the side that is illustrated;

FIG. 5 is a top plan view; and

FIG. 6 is a bottom plan view.

We claim:

The ornamental design for a tote case for tableware or the like, as shown and described.
